SOLVENT EXTRACTION OF ASPHALTIC RESIDUES

Rudolph C. Woerner, Homewood, Ill., assignor to
Sinclair Refining Company, New York, N. Y.,
a corporation of Maine

Application May 21, 1949, Serial No. 94,583

1 Claim. (Cl. 196—14.46)

1

Application Serial No. 94,708, of D. V. Fitz and E. J. Martin, filed May 21, 1949, and now abandoned, discloses a method of recovering useful oily compositions in sizable yields from petroleum asphalts by butane extraction. One of the critical factors in treating asphalt with a butane is securing an effective degree of contact and my invention relates to an improved method for obtaining effective asphalt-butane contact in a continuous contacting system which results in improved product quality and yield.

The effective contacting of butane solvent and asphalt is of practical significance since it is in great part determinative of the quality and yield of the extracted oil. Yield and quality are, of course, in the last analysis indicative of the commercial practicability of any such process, but in the treatment of asphalt with butane, yield and quality are in a sense mutually opposed. Thus yield increases with solubility, but in general, quality improves with sharpness of separation between the heavy oily constituents and the tarry or asphaltic constituents.

One of the difficulties in treating solid asphalt with a butane for oil recovery is that solubility decreases with increasing temperature. This complicates contacting efficiency, for under the operating temperatures required for commercially attractive yields the asphalt feed is very viscous. Direct contacting of feed and raw solvent tends to lump up the asphalt, causing apparatus plugging difficulties and resulting in poor recoveries. Moreover, I have found that it is difficult to mix in increments of solvent with the feed so as to increase fluidity before entering the extraction zone. Solubility is still too low at temperatures above the asphalt melting point. Since asphalt is plastic in character and not susceptible to pulverization, the intimate contact necessary for efficient extraction demands some liquid to liquid contact, and of course it is also desirable to handle the asphalt as a liquid for convenience and to hold down solvent requirements. I have discovered, however, that if contact between raw solvent and asphalt feed is minimized, and the feed is first contacted with an "oily" butane, for example, a circulating slurry stream from the extraction zone, handling and circulating difficulties are greatly reduced while both yield and product quality are significantly improved.

The extraction may be accomplished in one or more contacting stages with separation of an oil fraction in fat solvent and a spent asphalt fraction, followed by appropriate steps for solvent recovery and recycle, and stabilization of prod-

2

uct. For example, in single-stage contacting, the asphalt feed may be initially mixed with an "oily" butane, e. g., a circulating slurry of fat solvent and asphalt, before introduction to the extraction zone where it contacts the main solvent stream. In a two-stage system, for example, the fresh asphalt may be preliminarily mixed with an "oily" butane and then charged to a separating zone. A stream of partially spent asphalt is then admixed with fresh butane and charged to a second separating zone, from which the deoiled asphalt is recovered.

In the process the nature of the solvent is important; however, either n-butane or isobutane gives useful recoveries of good quality oils. The temperature must be below the critical temperature of the solvent and a pressure sufficient to maintain the solvent in the liquid phase is employed. Yield may be controlled conveniently through regulation of the top extraction temperature. It has been found that solvent to feed ratios above about 5 to 1 are necessary for useful yield, and solvent ratios above about 10 to 1 are usually highly desirable from the standpoint of yield and product quality. The relationship of solvent ratio and temperature, however, gives a degree of latitude in that lower solvent ratios may be partially compensated for by reducing temperature. With n-butane, yields of upwards of 40 volume per cent of oil may be obtained with a top extraction temperature of, say, about 230° F. at about 500 p. s. i. The solubility of isobutane is more limited, and yields of upwards of about 20 volume per cent are obtained at a top extraction temperature of, say, about 250° F. and a pressure of about 420 p. s. i.

My invention will be illustrated in Figures 1 and 2 of the accompanying drawings which represent the flow somewhat diagrammatically. Figure 1 is illustrative of a two-stage process embodying my invention; Figure 2 is illustrative of the invention adapted to a countercurrent contact in a column.

Figure 1 illustrates an essentially continuous contacting process for commercial extraction of heavy oils from asphalt with a butane solvent.

Fresh asphalt is introduced through line 10 and contacted with "oily" butane from lines 11 and 12. The contact mixture is preferably thoroughly agitated in mixing zone 13. The mixture is then passed by line 14 to the first stage settling zone 15, above which is situated stripping section 16 advantageously containing a series of steam coils 17, heated by steam introduced through line 18. The coils 17 maintain a differential temperature

between the top and bottom of the stripping column, thereby improving product quality and yield. The mixture of asphalt and "oily" butane is introduced above the asphalt-butane level 19 in the first settling zone. The oil-butane product is taken off through line 30 and is passed to a debutanizer (not shown). "Oily" butane is taken from the first settling zone by means of line 20 and is recirculated by contact with the fresh asphalt feed. Partially spent asphalt, containing butane, is taken from the bottom of the settling zone by line 21 and contacted with fresh butane entering through line 22. Part of this mixture may be recirculated as desired in the first settling zone by means of line 23. The fresh butane-partially spent asphalt mixture from line 21 is further contacted with another partially spent asphalt-butane slurry from the line 24, all are thoroughly mixed in mixing zone 25 and then passed into the second settling zone 26 by line 27, above the asphalt-butane level 19. Spent asphalt, containing butane, is taken from the second settling zone 26 by means of well 28 and line 29, from which it may be passed to a stabilizer (not shown). "Oily" butane is taken from this settling zone by line 30 and recirculated to the first settling zone, although a portion of the mixture may be contacted with the fresh butane-spent asphalt mixture by means of line 31.

The asphalt-butane levels 19 in the settling zones may be regulated by liquid level control valves, comprising a floating bulb 32 which releases valve 33 at the desired level. The process as described may also include pumps and valves as illustrated so as to accurately regulate the various flow streams and treatment zones.

Figure 2 illustrates a column contacting process embodying my invention.

Fresh butane, introduced through line 40, is contacted with a spent asphalt-butane mixture 42 taken from below the tar level in extraction zone 45 by line 41. This mixture is thoroughly agitated in mixing zone 43, most advantageously by use of mechanical stirrer 44, and passed to extraction zone 45 by line 46. An oil-butane product is taken off by line 47 and a spent asphalt-butane product by line 48. The oil-butane mixture is passed to a debutanizer (not shown), while the spent asphalt-butane product is passed to a butane stripper (also not shown). The extraction zone 45 is preferably an extraction column containing steam coils 49 in its upper portion so as to create a differential temperature between top and bottom, thereby resulting in improved quality and yield. Fresh asphalt feed is introduced through line 50, and contacted with a recycle slurry of "oily" butane from line 52. These components are thoroughly mixed in mixing zone 53, preferably by use of mechanical stirrer 54, and then are passed into the extraction zone 45 by line 56.

The spent asphalt-butane level 51 in the extraction zone 45 may be regulated by a liquid level control valve comprising a floating bulb 54 which releases valve 55 at the desired level. Suitably located pumps and valves may be used as illustrated.

The effect of contact efficiency on yield and product quality, together with the principles of my invention, will be illustrated in the following examples. In these examples the carbon residue, taken according to the Conradson method, is indicative of product quality as it tends to fix the other properties, including tackiness. High

viscosities are desired, together with a reasonably low optical density color.

The tests on the asphalt feed utilized are set forth below:

5	Specific gravity at 77° F./77° F.	1.052
Sft. pt.		156
Carbon residue, weight percent		27
Penetration at 77° F.		4

Example I

Extraction from asphalt with normal butane was first attempted by countercurrent contacting in a 4-inch by 15-foot extraction tower equipped with a top internal heater for the purpose of maintaining a differential temperature. The tower was packed with Raschig rings to improve contact, but upon contact of feed and solvent, the packing plugged solid with asphalt so that flow could not be continued.

Example II

A light stream of isobutane was mixed with asphalt feed in a commingler and the resulting mixture injected into about the middle of the column from which the Raschig rings had been removed. A main stream of isobutane was introduced into the column so as to contact the streams countercurrently. An isobutane-oil overhead was taken off, while the deoiled asphalt containing isobutane, was a bottoms product. The solvent-feed ratio was 14 to 1. A summary of the pertinent data for this run follows:

35	Carbon Residue, Wt. Percent	7	5
Yield, Vol. Percent		22	16
Viscosity at 210° F.		1,100	650
OD Color		2,000	1,200
Gravity, ° A. P. I.		12.5	13.5
Sft. Pt. of Spent Asphalt, ° F.		190	185
Extr. Col. Top Temp., ° F.		250	265

40 Although the process was operable, the contacting was not highly efficient, as indicated by the low yields and high carbon residues.

Example III

45 A similar extraction tower to that employed in Example II was used in this run. However, the light isobutane-fresh asphalt feed stream was, before injection into the column, further mixed with the main isobutane feed, the entire mixture then being thoroughly agitated in a vessel equipped with a mechanical stirrer and fed into the column at the middle. As a result there was no separate bottom isobutane entry, as in the previous example. The solvent-feed ratio 50 was about 14 to 1. A summary of the pertinent data follows:

60	Carbon Residue, Wt. Percent	7	5
Yield, Vol. Percent		28	20
Viscosity at 210° F.		1,100	650
OD Color		2,000	1,200
Gravity, ° A. P. I.		12.5	13.5
Sft. Pt. of Spent Asphalt, ° F.		216	195
Extr. Col. Top Temp., ° F.		225	255

65 When compared with Example II, the contacting was more efficient, as indicated by the somewhat higher yields at similar carbon residues.

Example IV

70 Using a similar extraction tower and mixing device as that employed in Example III, a side stream of isobutane-oil mixture from the tower was mixed with fresh asphalt and a light fresh isobutane stream. The resultant mixture was injected into the middle of the column. The bulk

of the fresh isobutane, amounting to about 85% of the total isobutane used, was injected directly into the bottom of the column. The over-all isobutane feed ratio was about 14 to 1. A summary of the pertinent data follows:

Carbon Residue, Wt. Percent	7	5
Yield, Vol. Percent	32	23
Viscosity at 210° F	1,100	650
OD Color	2,000	1,200
Gravity, ° A. P. I.	12.5	13.5
Sft. Pt. of Spent Asphalt	240	216
Extr. Col. Top Temp., ° F	208	244

This contact was most effective, as indicated by the higher yield at the comparable carbon residues of Example III. The side stream of oily isobutane permitted a highly effective contact with fresh asphalt at an exceedingly high oily butane to asphalt ratio. Thus efficient contact was obtained with the oily isobutane which permitted introduction of the bulk of the isobutane into the bottom of the column, thereby further enhancing the yields.

Example V

In a similar extraction tower and mixing device as that used in Example III, asphalt was contacted with normal butane. The light normal butane-fresh asphalt feed stream was, before injection into the column, further mixed with the main normal butane feed, the entire mixture then being thoroughly agitated in a vessel equipped with a mechanical stirrer and fed into the column at the middle. The solvent feed ratio was about 14 to 1. A summary of the pertinent data follows:

Carbon Residue, Wt. Percent	12	9
Yield, Vol. Percent	52	38
Viscosity at 210° F	3,500	1,500
OD Color	7,500	2,700
Gravity, ° A. P. I.	10	11.5
Sft. Pt. of Spent Asphalt	272	248
Extr. Col. Top Temp., ° F	260	282

Thus higher yields of oil can be obtained by use of normal butane in place of isobutane, but by sacrificing quality.

Example VI

In a similar extraction tower and mixing device as that used in Example III, a side stream of butane-oil mixture from the tower was mixed with fresh asphalt and a light fresh normal butane stream. The resultant mixture was injected into the middle of the column. The bulk of the

fresh normal butane, amounting to about 85% of the total normal butane, was injected directly into the bottom of the column. The over-all normal butane feed ratio was about 14 to 1. A summary of the pertinent data follows:

Carbon Residue, Wt. Percent	12	9
Yield, Vol. Percent	56	42
Viscosity at 210° F	3,500	1,500
OD Color	7,500	2,700
Gravity, ° A. P. I.	10	11.5
Sft. Pt. of Spent Asphalt	280	250
Extr. Col. Top Temp., ° F	256	278

The yields obtained in this contact are approximately 8% better than those of Example V for the same quality of oil. Again efficient contact was obtained with the oily butane, thereby permitting the bulk of the fresh normal butane to be introduced into the bottom for further countercurrent contact.

I claim:

In the production of oily compositions from asphaltic residua in which a mixture of butane solvent and asphalt in a solvent to asphalt ratio exceeding about 5:1 is mixed in an extraction zone at an elevated temperature below the critical temperature of the solvent and under super-atmospheric pressure sufficient to maintain the solvent in the liquid phase, and in which an upper layer of butane solvent rich in extracted oil and a lower layer rich in asphalt are later formed, the improvement which comprises withdrawing a portion of said upper layer from the extraction zone, intimately mixing said portion of the upper layer with the asphaltic feed before the asphaltic feed contacts the raw solvent stream and before the asphaltic feed is charged to the extraction zone, withdrawing a portion of said lower layer from the extraction zone, intimately mixing said portion of the lower layer with the raw solvent stream before the raw solvent stream contacts the asphaltic feed and before the raw solvent stream is charged to the extraction zone.

RUDOLPH C. WOERNER.
